(57) CLAIM

The ornamental design for a puzzle block toy, as shown and described.

DESCRIPTION

FIG. 1 is a perspective view of a puzzle block toy showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is another perspective view of the puzzle block toy of FIG. 1 showing it connected to another puzzle block for exemplary purposes only

FIG. 9 is another perspective view of the puzzle block toy of FIG. 1 showing it connected to multiple puzzle blocks for exemplary purposes only;

FIG. 10 is another perspective view of the puzzle block toy of FIG. 1 showing an alternate embodiment;

FIG. 11 is a top plan view thereof;

FIG. 12 is a bottom plan view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is another perspective view of the puzzle block toy of FIG. 10 showing it connected to another puzzle block for exemplary purposes only; and,

FIG. 18 is another perspective view of the puzzle block toy of FIG. 10 showing it connected to multiple puzzle blocks for exemplary purposes only.

The dashed broken lines are included for the purpose of illustrating environmental structure that forms no part of the claimed design.

1 Claim, 12 Drawing Sheets
